ROLLER SKATE

Filed June 19, 1931

FIG. 2

FIG. 3

UNITED STATES PATENT OFFICE

FRANK R. SMITH, OF CLEVELAND, OHIO

ROLLER SKATE

Application filed June 19, 1931. Serial No. 545,431.

My invention relates to improvements in roller skates and more particularly to ball bearing roller skates.

The primary object of the invention is to provide a skate wherein the wheels are sectional and contain ball bearings which permit less friction during the use of the skates, and the mounting of a resilient tire on the wheels to insure a minimum of shocks to the user when the skates are in motion.

Another object is the novel construction and the easy running qualities obtained by the use of the spring leaves in conjunction with the single wheels forward and back and their forked arms.

Other objects will be apparent from the following description in connection with the accompanying drawing which illustrates the mechanical features of the skates, and in which:

Fig. 1 is a side elevational view with the frame of the skate in section.

Fig. 2 is a vertical transverse section taken on line 2—2 of Fig. 1.

Fig. 3 is a section taken on line 3—3 of Fig. 2.

Fig. 4 is a section on the line 4—4 of Fig. 1.

Referring to the drawing: the heel plate is noted at 10 riveted at 11 to a foot spring plate 12 and at 9 to a leather heel support 8 which fits between the plate 10 and the foot 7, said foot plate being cut out at 13 to form an aperture 14 and the cut out portion is bent downward forming a flange 15. The plate 12 is bent in such manner as to form a rise 16 just back of the ball of the foot 7 which forms a resilient rest for the foot of the skater.

The reinforcing spring plate 17 is riveted to foot plate 12 at 18 and 19, and an adjusting clamp 20 with adjusting screw 21 fits across the plates 17, 22 and 23, the last two being convex spring plates riveted together at 24 and 25, plate 25 having forked arms 29 and 30 at opposite ends and extending at an angle

from said plate 25 and are integral with the plate. Mounted between the arms 29 and 30 are the wheels, each of which consists of a shaft 31, flattened at each end 32 and 32a, said ends being threaded to receive the nuts 33 and 33a; on each shaft is a cone shaped bearing race 34, ball bearings 35 and bearing cups 36 and 37 which have countersunk apertures 36a and 37a in their outer surfaces into which a felt, leather or rubber washer 38 is fitted. Bearing cup 36 is threaded at 39 to be turned into the bolted flange 40, the bolts 41 being inserted through the flange 40a and the wheel discs 42 and 42a and the center supporting plate 43 and the bolt flange 40 thus forming a unit.

When the wheel is assembled and bolted together the prongs 29 and 30 are slipped over each end of the shaft 31 and held in position by the nuts 33 and 33a. The disc 40 and 40a have at their periphery rims 44 and 44a with a peripheral tire seat or groove 45 in which a tire 46 is mounted being cast upon the center supporting plate 43.

A toe clamp 47 of the usual kind is carried by the forward section of the foot plate 12 and an instep strap or heel support 8 is riveted to the heel plate 10.

When the body is resting fully upon the skates the weight flattens the springs 22 and 23 slightly and thus spread the wheels further apart giving a resilient spring like motion when in use.

I claim:

1. A rollerskate comprising an upperspring foot plate, a lower, upwardly bowed spring plate clamped to the under side of the foot plate, said lower plate having a fork at each end, and a wheel supported in each fork.

2. A roller skate as in claim 1, and a reinforcing spring plate fixed to the under side of the foot plate and resting upon the lower plate.

3. A roller skate as in claim 1, the foot

plate having a longitudinal flange depending therefrom beside the lower plate.

4. A roller skate comprising an upper foot plate, a reinforcing spring plate fixed to the under side thereof, a convex spring plate on top of which the reinforcing plate rests, an adjustable clamp extending around all of said plates, the convex spring plate having forks at the ends, and a wheel in each fork.

10 In testimony whereof, I do affix my signature.

FRANK R. SMITH.
